ANDREW M. HARKNESS, OF NYACK, NEW YORK, ASSIGNOR TO GENERAL CHEMICAL COMPANY, OF NEW YORK, N. Y., A CORPORATION OF NEW YORK

WASTE HEAT BOILER

Application filed August 24, 1927. Serial No. 215,027.

This invention relates to heat-transfer systems, and more particularly to waste heat boilers.

In the manufacture of sulfuric acid by the contact process the primary gases (SO_2 , O_2 , etc.) from which the sulfuric acid is ultimately formed are at a high temperature when they leave the pyrites or brimstone burners. In order for the catalytic action which converts these gases to sulfur trioxide to take place efficiently the temperature of these primary gases should undergo a substantial reduction prior to their being admitted to the catalytic converters.

It has been suggested to utilize in this relation a heat transerrer of the waste heat boiler type by means of which the temperature of the gases could be effectively reduced, and the heat absorbed made use of for the generation of power or other purposes. The peculiarities of sulfuric acid manufacture, however, render the ordinary waste heat boilers but poorly suited for this purpose.

The ordinary waste heat boilers are commonly characterized by the fact that the conduit pipes, which conduct the gases etc. through the cooling medium, are secured to the jacket of the cooling chamber at a plurality of points, usually at both ends, and these conduits are generally arranged horizontally within the chamber. By reason of this customary rigid securing of the conduits at a plurality of points, the possibility is always present of the conduits becoming disrupted, or released from their fastenings because of uncompensated expansion or contraction due to temperature changes.

The leaks caused by such disruption or release would not be particularly detrimental in ordinary applications of the boiler, unless the leakage were of considerable magnitude, but in sulfuric acid systems, such for example as those based on the contact process, even a slight leakage within the boiler would present serious aspects. The water or steam thus admitted into the system in which sulfuric anhydride is produced would jeopardize the entire apparatus and process, the corrosion factor presented thereby being alone

of sufficient moment to render most undesirable such an application of the usual boiler.

Moreover, the gases which would come to the boiler in a sulfuric acid system would be quite appreciably laden with dust, and these horizontal conduits would promote dust deposition on the walls of the conduit, particularly at the bottom, with a resultant diminution in the heat transfer efficiency of the conduit. This dust layer, furthermore, promotes condensation of sulfuric acid from the gases, some slight amount of which is always present even prior to the catalytic conversion step, and the condensed acid attacks the steel of which the conduit is constructed. By the formation of a dust layer a region insulated from the hot gases in the conduit is provided between such layer and the externally cooled, highly conductive wall of the conduit, and into this cooled region the sulfuric acid will penetrate and will condense when the temperature of the cooling medium in contact with the conduit wall too closely approaches that at which sulfuric acid will condense (approximately 400° F.).

The object of my invention is to provide an improved construction in a heat transfer system of the waste-heat boiler type which will include proper provision for expansion and contraction of the conduits which are in contact with the heat transfer medium within said boiler.

A further object of my invention is to provide a construction of the order noted in which the possibility of dust deposition within said conduits, and the formation and retention of condensation products therein will be reduced to a minimum.

With the above and other objects in view, the manner in which I accomplish the same will be apparent from the following specification taken in conjunction with the accompanying drawings in which

Fig. 1 is a vertical sectional view of a waste heat boiler embodying my invention, with parts broken away, and

Fig. 2 is a horizontal section of the same, taken along the line 2—2, Fig. 1.

Referring to the drawings, and in particu-

lar to Figure 1, reference numeral 3 designates a steel outer shell or jacket which defines the cooling chamber 4, of a waste heat boiler, the bottom of which jacket is flanged 5 as at 5 to form openings 6, these flanges providing foundations for the securement of a pair of conduit pipes 7, 8 constituting the arms of an inverted U-shaped steel conduit 9. The upper ends of the pipes 7, 8 constituting the arms of the inverted U-shaped conduit are connected together by a coupling 10, riveted or otherwise secured thereto.

The mounting of the conduit 9 in the chamber 4 is characterized by the restriction of the 15 securement of its arms to the flanges 5 to a substantially localized area or point in the length of each arm, by rivets 11 or other means, the portion of the conduit above the area of securement being left substantially 20 unsecured. It will be seen that by this arrangement the arms of the inverted U-shaped conduit are secured to the jacket only over localized areas located respectively at the points of entry of the arms into the jacket; 25 the portion of the conduit projecting into the chamber, and particularly the terminus of said projecting portion (in this instance the top of the inverted U) being left free of securement. This conduit is mounted within 30 the chamber 4 for conducting therethrough the gases to be cooled (i. e. SO₂, O₂, etc.), the gases entering and passing upwardly through the passage in the arm 7, and downwardly through the passage in the arm 8, 35 whence they are conducted to the converters to be converted into sulfur trioxide.

A feed pipe 12 is mounted in a bushing in the wall of jacket 3 and leads into the chamber 4 for introducing therein the water or 40 other heat transfer medium, and in the top of the jacket 3, a pair of steam nipples 13 and 14 are provided, the nipple 13 serving as an outlet for the steam or vapor generated in the boiler and the nipple 14 being connected 45 with a suitable safety valve (not shown). The usual manhole 15, handholes 16, and blow off opening 17 are provided for affording access to the interior of the jacket for cleaning and repairing the same. Reference numerals 50 18 and 18' designate respectively the usual pressure and water gauges which may be of any suitable and well-known type.

In the boiler of the present application I use two conduits 9, as best shown in Figure 55 2, although any desired number may be provided. For maintaining these rather elongated conduits in proper vertical relation, I provide, supplementary to be localized securing means 11, a guiding brace 19. This brace 60 19 consists of an outer frame work 20 riveted or otherwise attached to the jacket 3, to which frame work a series of suitable steel straps 21 are secured, each strap confining one of the arms 7, 8 of the conduits 9 between itself 65 and the adjoining sides of the frame work

20. This brace eliminates the possibility of the conduit pipes 9 working loose from or weakening their connection with the flanges 6 by leaning away from the original vertical position in which they were secured. The 70 straps 21 but lightly contact with the conduits 9 and offer no appreciable resistance to expansion or contraction of said conduits, their function being simply to maintain the conduits in position and not to secure them. 75

When the boiler is in operation the conduits are completely covered by the water or other heat transfer medium as indicated by the water level shown by the dotted line in Fig. 1.

The construction I have described provides 80 a very efficient waste-heat boiler and satisfactorily eliminates the dangers arising from expansion or contraction, and corrosion of the conduits. By means of the localized securement of the conduit, leaving its major portion 85 and the inner terminus of the portion projecting into the chamber with no impediment to expansion or contraction, there is no tendency toward disruption on the part of the conduit arising from external resistance to its 90 longitudinal expansion or contraction. The free upper portion of the conduit will present an outlet or take-up for the longitudinal expansion or contraction in the conduit produced by even considerable temperature 95 changes with no deleterious effects upon the conduit or its securement to the jacket.

In addition, such a construction permits the use of riveted, welded, or screwed joints 100 in the securement of the conduit to the jacket, rather than the common rolled joints, which exhibit a tendency toward ready leakage.

Further, the vertical arrangement of the 105 passages in the conduit pipes affords but slight opportunity for a dust coating being formed, and such inclination as there might be toward a dust deposition in the limited horizontal area provided by the coupling section 10 is opposed by the strong eddy currents 110 prevailing in the section 10 and by the rounded character of the lower part of the section. The continuous, vertical conduit passages in the cooling chamber reduce the horizontal travel of the gases while in the cooling chamber to a minimum, and thus avoid any appreciable deposition of dust in the conduit 115 within the cooling chamber.

The inverted U-shaped type of conduit which I employ presents a type of construction which affords a maximum of vertical 120 structure with a minimum of horizontal structure, a relation extremely desirable in the present application, and such an arrangement presents a very extensive exposed length of conduit to the cooling medium which entirely surrounds the same while occupying but a comparatively small space. The inverted U-shaped conduit construction is particularly well adapted, moreover, for the localized securement desired, the attachment of 125 130

the conduit at the lower portion of the arms of the **U** presenting a very stable two point supporting arrangement.

It will be clear that while I have shown 5 the **U**-shaped conduit as constructed of a plurality of elements, it may be formed as a single element.

In referring to the conduit as having the shape of an "inverted **U**" I mean simply a 10 construction having the general conformation of a **U**, whether the arms be vertical or otherwise, so positioned in respect to the attaching medium, in this instance the boiler jacket 3, that the bend or curve of the **U** 15 is spaced from said medium by the arms of said **U**.

When I refer to the conduit pipes as "unaligned" I mean that the longitudinal axes of the pipes do not lie in a single straight line.

20 While I have stressed the applicability of my waste-heat boiler particularly in relation to sulfuric acid production, it is obvious that the troublesome factors indicated, which are overcome by my construction, are not necessarily confined solely to the production of 25 that material, and the solution which the construction offers to the basic elements of the problem is equally applicable, with reasonable modifications, to apparatus used in other 30 and similar relations.

The foregoing discloses a preferred embodiment of my invention, but it is to be understood that I do not limit myself to the specific form disclosed and consider my invention to contemplate all equivalent constructions and arrangements of parts such as may fall within the scope of the appended 35 claim.

I claim:

40 A waste heat boiler for cooling hot dust-laden gases in the contact process of making sulfuric anhydride comprising an enclosing shell adapted to contain water and steam under pressure, said shell having opposing end 45 walls, a plurality of **U**-shaped gas conduits projecting into said shell through an end wall and attached thereto, and free from the end wall of the shell most remote from the point of attachment of the conduits, said conduits being entirely below the water level in 50 said shell and having an inner contour such as to operate in conjunction with the gas currents passing therethrough against the deposition of substantial amounts of dust on the 55 inner portions of said conduits within the shell, a steam outlet associated with the shell above the liquid level therein, and means including bracing elements loosely engaging the conduits and attached to the shell, for 60 maintaining said conduits in substantially the position in which they are secured to said shell.

In testimony whereof, I affix my signature.
ANDREW M. HARKNESS.
